(57) **CLAIM**

The ornamental design for an electronic device cover, as shown and described.

DESCRIPTION

FIG. 1 is a first perspective view of an electronic device cover, taken from above;

FIG. 2 is a second perspective view of the electronic device cover of FIG. 1, taken from below;

FIG. 3 is a back view of the electronic device cover of FIG. 1;

FIG. 4 is a front view of the electronic device cover of FIG. 1;

FIG. 5 is a left-side view of the electronic device cover of FIG. 1;

FIG. 6 is a right-side view of the electronic device cover of FIG. 1;

FIG. 7 is a bottom view of the electronic device cover of FIG. 1; and,

FIG. 8 is a top view of the electronic device cover of FIG. 1.

The broken lines in the drawings represent portion of the electronic device cover which form no part of the claimed design.

The Applicant reserves the right to convert some or all of the broken lines to solid lines during the course of prosecution and/or in one or more continuation applications, since the figures convey that the inventors had possession of the features shown in broken lines, individually and in combination with one or more other features shown in broken lines, as of the date of filing.
